PAY INDICATOR

Andres Flores Laiet, Caracas, Venezuela

Application March 22, 1935, Serial No. 12,457

7 Claims. (Cl. 273—142)

This invention relates to new and useful improvements in a commercial advertising system.

The invention proposes the construction of a device by which a commercial advertising system or pay indicator may be very advantageously and interestingly carried out.

It is proposed to arrange the device with a rotative disc divided into sections, preferably one of which is imprinted "Don't Pay"; several of which are imprinted with percentages of discounts, and the great majority of which are imprinted with "Pay", and to incorporate the disc in conjunction with a stationary pointer and means for rotating the disc for a short period of time only, so that it comes to a stop with the pointer indicating one section.

The plan which may be carried out with the use of the device is as follows: A buyer comes in and purchases the merchandise he needs at a price that he would pay at any other establishment. After having paid the cashier operates the above described apparatus and if it indicates the words "Don't Pay", the money is refunded to the purchaser; if it indicates the words "Pay 25%", "50%", etc., the difference is returned to the purchaser; and if it indicates the word "Pay", the money is retained by the cashier. It is pointed out that the purchaser has paid for the merchandise he needs at a price that he would have paid at any other establishment without risking any money.

The advantage of the system is that it stimulates interest in a particular establishment, and that there is a chance that the customer may obtain merchandise free of charge, or may obtain it at a discount. While the opportunity for the customer to obtain any advantage is small, still it is an attractive system of advertising which is very effective.

The invention still further proposes the construction of a device as mentioned which is adapted to be operated electrically, or manually, at will.

More particularly, the invention contemplates the provision of an electric mechanism for operating the disc, which mechanism includes a control gear adapted to be shifted, and a mechanical mechanism for operating the disc, but arranged so that when a lever is placed in a certain initial position, the gear is shifted for connecting the electrical device.

Still further the invention proposes the construction of a device as mentioned which is simple and durable and which can be manufactured and sold at a reasonable cost.

For further comprehension of the invention, and of the objects and advantages thereof, reference will be had to the following description and accompanying drawings, and to the appended claims in which the various novel features are more particularly set forth.

In the accompanying drawings forming a material part of this disclosure:

Fig. 1 is a front elevational view of a device constructed according to this invention. 10

Fig. 2 is a transverse sectional view taken on the line 2—2 of Fig. 1.

Fig. 3 is a transverse sectional view taken on the line 3—3 of Fig. 1.

Fig. 4 is a rear elevational view of Fig. 2. 15

Fig. 5 is a fragmentary enlarged sectional view taken on the line 5—5 of Fig. 4.

Fig. 6 is a fragmentary enlarged sectional view taken on the line 6—6 of Fig. 4.

Fig. 7 is a fragmentary enlarged sectional view taken on the line 7—7 of Fig. 4. 20

Fig. 8 is a rear elevational view of a device constructed according to a modification of the invention.

Fig. 9 is a side elevational view of Fig. 8 seen 25 as though looking from the right hand side.

Fig. 10 is a fragmentary sectional view as though taken on the line 10—10 of Fig. 8.

Fig. 11 is an elevational view taken on the line 11—11 of Fig. 10. 30

The "Pay" indicator, according to this invention, comprises a hollow body 10 rotatively supporting a horizontal shaft 11 which extends from both sides of the body. A disc 12, which is divided into a plurality of sections 13, 13^a, 13^b and 13^c, 35 is fixed upon one end of the shaft 10. A pointer 14 is mounted upon the body 10 and extends over a portion of the disc for indicating one of the sections. A master gear 15 is fixed upon the other end of the shaft 11. A fly wheel 16 is housed 40 within the hollow body 10 and is fixed upon the shaft 11.

The sections of the disc 12 are inscribed with different indicator words. All of the sections 13, which are in the great majority, contain the 45 words "Pay"; the section 13^a the words "Don't Pay"; and the sections 13^b and 13^c contain the word "Pay", and a certain disc such as 25% or 50%, etc.

A gear 18 is free upon the shaft 11 and is connected to the shaft by means of a one way ratchet connection. This ratchet connection consists of a spring pressed pawl 19 upon one side of the gear 18 meshing with a one way ratchet wheel 20 fixed upon the shaft 11. The ratchet wheel 20 55

is arranged between the fly wheel 16 and the gear 18. A pinion shaft 21 is rotatively mounted upon the body 10 and is provided with a pinion 22 which is non-rotative and slidably mounted thereon. The pinion 22 is engageable with the gear 18. A resilient means, in the form of a spring 23, is arranged upon the pinion shaft 21 and acts against the pinion 22 for normally holding it in an idle position.

10 The pinion shaft 21 is connected with an electric motor drive. More particularly, a bevel gear 24 is fixed upon the pinion shaft and meshes with a small pinion upon the shaft of an electric motor 25. This electric motor is operated by a push 15 button switch 26. The electrical connections are not shown on the drawings since they form no part of the invention and will be readily understood by those familiar with the art. The electrical connection is such that when the push 20 button switch is closed, the motor operates, and when released, the motor ceases functioning.

A lever 27 is pivoted on the outside of the hollow body 10 and has a gear sector portion 27' engageable with the master gear 15 for the purpose of spinning the latter gear. The arrangement is such that the outer end of the handle 27 may be quickly and smartly moved in one direction so that the sector gear engages the master gear to accomplish the turning. The lever 30 27 is adapted to be held in several positions. There is a spring catch 29 mounted upon the body 10 and adapted to hold the lever 27 in a position with the gear sector 27' above the master gear 15. There is a second spring catch 30 also mounted on the body 10 which is adapted to hold the lever 27 in a position with the segment gear portion 27' below or adjacent the gear 15. There is a third spring catch 31 also mounted on the body 10 which is adapted to hold the lever 27 in the position indicated by the dot and dash lines 27^a. This latter position, for the purpose of this specification, is called the "initial" position.

The lever 27 is fixed upon a spindle 32 which 45 extends through the wall of the hollow body 10, and at its inner end is provided with a finger 32' engaging above an arm 33 which has one end 33' pivotally mounted upon the spindle. The free end of the lever 33 is in the form of a fork 50 portion 33^a which engages upon a shoulder formed upon the hub portion of the pinion 22. The finger 32' is so arranged that when the lever 27 is in the initial position, the finger presses the lever 33 downwards so that the pinion 22 is 55 moved down against the action of the spring 23, and is in its operative position. When the lever 27 is so moved that the handle end moves anti-clockwise, the finger 32' merely idles, and the lever 33 and the spring 23 raise the pinion 22 to 60 its inoperative position.

A fixed stop 35 projects from the outer portion 65 of the body 10 for limiting pivoting of the lever 27 into the position in which the segment 27' is above the master gear 15. An adjustable pin 36 limits pivoting of the lever 27 to the second-mentioned position, the ones in which the segment 27' is to the side of the master gear 15. The adjustable pin 36 is slidably arranged in a bayonet opening 37 in the wall of the body 10 so that it 70 may be moved to the position indicated by the dot and dash lines 36', in which position the lever 27 may be moved to its "initial" position.

The shaft 11 is rotatively supported in ball 75 bearings 40 mounted upon the walls of the body 10. A ratchet 41 is fixed upon the side of the

fly wheel 16 and is engaged by a resilient finger 42 mounted upon one of the walls of the body 10 so that the shaft 11, when it comes to a stop, will be in a position in which the pointer 14 indicates one of the sections upon the disc 12. 5

The operation of the device is as follows: If it is desired that the disc 12 be operated electrically, the lever 27 is moved to its "initial" position. The push button may then be held closed for energizing the motor which drives the disc 10 12. When the push button is released the disc 12 continues rotating because the pawl 14 is now over-running the ratchet 20 which is standing stationary. Thus, the disc 12 is free to rotate until it naturally stops at some position indicating whether the purchaser is a winner.

The device may be operated manually by moving the lever 27 and shifting the stop 36 into position shown in full lines in Fig. 4. Now the lever 27 may be smartly snapped in one direction to 20 cause rotations to be transmitted to the shaft 11 and the disc 12. Since the segment 27' passes the master gear 14, the shaft 11 will be free to rotate until it naturally stops. When the lever 27 is moved in the opposite direction, the parts 25 merely idle because of the pawl 19 and the ratchet 20. The catches 29 and 30 hold the lever 27 in either position.

A pointer and handle 45 project radially from the shaft 11 by which the disc 12 may be manually turned to a position in which the indicator 14 points to the "Don't Pay" section. The cashier normally resets the device into this position so as to attract the attention of the customers and impress them with the fact they have a chance to 35 receive free of all charges, or at a reduction, the merchandise that they intended to purchase and pay for.

In the form of the invention illustrated in Figs. 8-11 inclusive, a printing device has been 40 incorporated therein for the purpose of printing the result of the pay indicator upon a piece of paper which may be handed to the customer, or may be retained as a record by the establishment. The printing device comprises a bracket 45 50 50 which is attached upon the body of the device and which supports a gear speed reduction unit 51 comprising a plurality of gears. The speed reduction unit 51 is provided with a worm 51' at one end meshing with a worm pinion 52 55 upon a shaft 53 rotatively supported on the body of the machine and equipped with a printing wheel 54. This printing wheel has its periphery engraved or formed in any other manner to correspond with the notations on the disc 12. A gear 55 is mounted upon the shaft 53 and meshes with a gear 56 fixed upon the shaft 11.

The speed reduction 51 terminates at the other end in a gear 51^a upon a shaft 57 and supports a roll of paper 58. One end 58' of this roll of 60 paper engages through a grooved bracket 59 located beneath the wheel 54. A lever 60 is pivotally mounted intermediate of its ends upon a spindle 61 mounted on the bracket and has its other end equipped with a flat press surface 62. 65 This press surface 62 is located beneath the bracket 59 and operates through a corresponding opening in the bracket. A coaxial spring 63 is mounted upon the spindle 61 and normally urges the block 62 into its lowered position.

The operation of the device is as follows: Simultaneous with the operation of the disc 12, the printing wheel 54 will turn in synchronization therewith due to the meshing gears. When the disc 12 finally comes to rest, the inscription there- 70 75

on beneath the pointer 14 will correspond with the inscription located in the lowermost central position of the printing wheel 54. The cashier or operator may depress the handle 60 for forcing the end 58' of the paper against the printing surface so that the indication is printed thereon. The printing wheel 54 is manually inked, preferably by holding an ink pad against it. If desired, an inking attachment may be included.

10 The web of paper from the roll 58 will be continuously moved during the turning of the disc 12 but at a reduced rate of speed due to the gear reduction unit.

While I have illustrated and described the preferred embodiment of my invention it is to be understood that I do not limit myself to the precise construction herein disclosed and the right is reserved to all changes and modifications coming within the scope of the invention as defined 20 in the appended claims.

Having thus described my invention, what I claim as new and desire to secure by United States Letters Patent is:

1. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft 25 and provided with a one way ratchet connection with the shaft, a pinion shaft for connecting with a source of rotation and bearing a pinion relatively non-rotative and slidable thereon and engageable with said gear, resilient means holding 30 said pinion in an idle position, a lever pivoted on the outside of said body and having a gear section portion engageable with said master gear to spin the latter, an "initial" position for the lever, and means for engaging said pinion with 35 said gear when the lever is in the initial position.

2. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft 40 and provided with a one way ratchet connection with the shaft, a pinion shaft for connecting with a source of rotation and bearing a pinion relatively non-rotative and slidable thereon and engageable with said gear, resilient means holding 45 said pinion in an idle position, a lever pivoted on the outside of said body and having a gear section portion engageable with said master gear to spin the latter, an "initial" position for the lever, and means for engaging said pinion with 50 said gear when the lever is in the initial position, and a flywheel fixed on said shaft.

3. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft 55 and provided with a one way ratchet connection with the shaft, a pinion shaft for connecting with a source of rotation and bearing a pinion relatively non-rotative and slidable thereon and engageable with said gear, resilient means holding 60 said pinion in an idle position, a lever pivoted on the outside of said body and having a gear section portion engageable with said master gear to spin the latter, an "initial" position for the lever, and means for engaging said pinion with 65 said gear when the lever is in the initial position, and catches for holding the lever in several stationary positions.

with said gear when the lever is in the initial position, a ratchet fixed on said shaft, and a pawl engaging said ratchet for the purpose of causing the disc to stop in a position in which the pointer indicates one of the sections of the disc. 5

4. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft and provided with a one way ratchet connection with the shaft, a pinion shaft for connecting with a source of rotation and bearing a pinion relatively non-rotative and slidable thereon and engageable with said gear, resilient means holding 10 said pinion in an idle position, a lever pivoted on the outside of said body and having a gear section portion engageable with said master gear to spin the latter, an "initial" position 15 for the lever, and means for engaging said pinion with said gear when the lever is in the initial position, the pinion shaft having a square portion, and the gear having a square opening slidable on 20 the square portion. 25

5. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft and provided with a one way ratchet connection with the shaft, a pinion shaft for connecting with a source of rotation and bearing a pinion relatively non-rotative and slidable thereon and engageable with said gear, resilient means holding 30 said pinion in an idle position, a lever pivoted on the outside of said body and having a gear section portion engageable with said master gear to spin the latter, an "initial" position 35 for the lever, and means for engaging said pinion with said gear when the lever is in the initial position, said engaging means comprising a spring acting against a stationary part and said 40 pinion. 45

6. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft and provided with a one way ratchet connection with the shaft, a pinion shaft for connecting with a source of rotation and bearing a pinion relatively non-rotative and slidable thereon and engageable with said gear, resilient means holding 50 said pinion in an idle position, a lever pivoted on the outside of said body and having a gear section portion engageable with said master gear to spin the latter, an "initial" position 55 for the lever, means for engaging said pinion with said gear when the lever is in the initial position, and catches for holding the lever in several stationary positions. 60

7. In a pay indicator for a commercial advertising system, a hollow body, a shaft extending through the body, a disc divided into sections fixed on one end of said shaft, a pointer on the body extending over the disc, a master gear on the other end of the shaft, a gear free on the shaft 70 and provided with a one way ratchet connection with the shaft, a pinion shaft for connecting with a source of rotation and bearing a pinion relatively non-rotative and slidable thereon and engageable with said gear, resilient means holding 75

said pinion in an idle position, a lever pivoted on the outside of said body and having a gear section portion engageable with said master gear to spin the latter, an "initial" position for the lever, means for engaging said pinion with said gear when the lever is in the initial position, and

catches for holding the lever in several stationary positions, stops being arranged upon the body for limiting motion of the lever, one stop being adjustable to a position which allows the lever to move to the said initial position.

ANDRES FLORES LAIRET.
